UNITED STATES PATENT OFFICE

AUGUST H. WILMS, OF CHEYENNE, WYOMING

SPARK ARRESTER AND CRUSHER

Application filed July 21, 1926. Serial No. 124,088.

This invention appertains to spark arresters for locomotives, but is susceptible for use on stationary steam engines and the like.

One of the primary objects of the present invention is to provide a spark arrester and crusher embodying means disposed in the path of the products of combustion for catching the cinders and sparks and reducing the same to a powder, whereby the same will not 10 interfere with the draft of the locomotive.

Another salient feature of the invention is the provision of a plurality of rotatable cylinders arranged one within the other and in the path of the products of combustion and 15 having openings therein for permitting the passage of smoke therethrough and for receiving the cinders or sparks, the screens or cylinders functioning for retarding the sparks and crushing the same to a powder.

20 A further object of the invention is to provide novel means for rotatably mounting the cylinders in the smoke box of the locomotive and novel means for mounting the cylinders relative to one another whereby the proper grinding of the cinders and sparks 25 will take place.

20 A further object of the invention is the provision of novel means for rotating the outer cylinder from a desired moving part of 30 the locomotive, whereby the cylinders will be positively operated.

35 A still further object of the invention is to provide a novel cinder and spark arrester and crusher of the above character which will be durable and efficient in use, one that will be simple and easy to manufacture and one which can be placed upon the market and incorporated with a conventional locomotive at a comparatively small cost.

40 With these and other objects in view, the invention consists in the novel construction, arrangement and formation of parts, as will be hereinafter more specifically described, claimed and illustrated in the accompanying drawings, in which drawings:

Figure 1 is a fragmentary side elevation of a locomotive showing my improved device incorporated therewith,

Figure 2 is a fragmentary front elevation of a locomotive partly broken away showing the improved device incorporated therewith,

Figure 3 is a fragmentary top plan view of the locomotive showing the improved spark and cinder arrester incorporated therewith,

Figure 4 is a fragmentary vertical longitudinal section through the locomotive showing the arrester in operative position therein,

Figure 5 is a transverse section through the boiler showing the novel spark arrester and crusher positioned therein, certain of the cylinders of the spark arrester and crusher being shown broken away and in section to illustrate the arrangement of the slots therein,

Figure 6 is an enlarged detail section through the cylinders of the spark arrester and crusher illustrating the arrangement thereof relative to one another,

Figure 7 is an enlarged fragmentary longitudinal section through the cylinders, illustrating the arrangement thereof relative to one another and the slots therein.

Referring to the drawings in detail, wherein similar reference characters designate corresponding parts throughout the several views, the letter A generally indicates a conventional locomotive and B the novel spark arrester and crusher therefor.

As stated the locomotive is of the usual type and embodies the conventional boiler 10 having the conventional smoke box 11 therein forwardly of the flue sheet 12. Communicating with the smoke box is the smoke stack 13.

Partitions 14 and 15 are arranged in the smoke box and these partitions are spaced

at their forward ends, as at 16 for receiving the novel spark arrester and crusher B.

Arranged directly below the smoke stack 13 is the exhaust 17 which opens through the lower end of the smoke box and communicates with the interior of the smoke box through the partition 14. To one of the drive axles 18 of the locomotive is secured a sprocket wheel 19 the purpose of which will be later described.

10 The improved spark arrester B comprises inner and outer cylinders 20 and 21 and an intermediate cylinder 22. The intermediate cylinder 22 is of a slightly less diameter than the outer cylinder, while the inner cylinder 20 is of a slightly less diameter than the intermediate cylinder 22. The outer cylinder 21 is provided with end heads 23 and these heads are connected at their axial center to a transversely extending shaft 24. The shaft 24 has its opposite ends journaled respectively in the boiler 10 and in the cover plate 25, which is provided for the opening 26 in the smoke box. This opening 26 provides 15 means whereby the cylinders 20, 21 and 22 can be placed in or removed from the smoke box 11. Any suitable type of fastening elements 27 is provided for holding the plate in position.

30 The intermediate and inner cylinders 22 and 20 are loose and unsupported by the shaft 24 and the cylinder 20 rests on the inner surface of the cylinder 22, while the cylinder 22 rests on the cylinder 21 at the bottom thereof 35 for a purpose hereinafter described.

The outer cylinder 21 is provided with circumferential rows of staggered slots 28, while the intermediate cylinder 22 is provided with longitudinal rows of staggered slots 29. The inner cylinder 20 is provided with rows of slots 30 similar to the rows of slots 28.

40 The slots in the several cylinders differ in width. Those in the outer cylinder are wider than those in either the intermediate or the inner cylinder and the slots in the intermediate cylinder are wider than those in the inner cylinder.

45 The outer cylinder 21 is positively driven from any preferred part of the locomotive, such as the valve gear or the like. In the present instance, however, I have shown the same operated from one of the drive axles of the locomotive. To carry out this arrangement the shaft 24 has keyed or otherwise secured thereto a spur gear 31 which meshes 50 with a pinion 32 secured to a stub shaft 33. This stub shaft is rotatably supported by the plate 25 and a bracket 34 secured to said plate. A sprocket wheel 35 is likewise secured to the stub shaft and is in alinement with the sprocket wheel 19 on the axle 18. These sprocket wheels 19 and 35 have trained about the same a drive sprocket chain 36. This mechanism functions perfectly to bring 55 about the desired results, but as stated the

cylinder can be driven in any desired way. Due to the fact that the cylinder 22 is in engagement with the cylinder 21 the same will be rotated thereby and likewise the inner cylinder 20 is rotated due to its contact with the cylinder 22.

60 In operation of the improved device, the products of combustion flow through the cylinders 20, 21, 22 and out of the smoke stack 13. The cinders and sparks are caught by the cylinders and drop between the cylinders 21 and 22 and between the cylinders 20 and 21, where the same are crushed. This absolutely precludes the passage of live sparks through the stack and thus the difficulties associated with the issuing of live sparks from the locomotive are entirely eliminated.

65 Changes in details may be made without departing from the spirit or scope of the invention.

85 I claim:

1. In a locomotive provided with a smoke box and a stack, a spark arrester and crusher, comprising inner, outer and intermediate rotatable cylinders, the inner and outer cylinders having circumferential rows of slots staggered and the slots of the inner cylinder being of less width than those in the outer cylinder, the intermediate cylinder having longitudinal rows of slots staggered, the last mentioned slots being of less width than the slots of the outer cylinder but of a greater width than the slots of the inner cylinder, and means co-acting with said outer cylinder for directing the products of combustion 90 through said cylinders.

2. In a locomotive provided with a smoke box and a stack, spaced partitions in the box defining an opening, a positively driven rotary foraminous cylinder in said opening, and a foraminous cylinder of less diameter than the first disposed therein and supported by the bottom thereof.

3. The combination with a locomotive comprising a boiler having a smoke box and stack, of partitions in the smoke box spaced to define an opening leading to the stack, a rotatable shaft carried by the smoke box, a foraminous cylinder secured to the shaft and arranged in the opening, means for rotating the shaft from an operating part of the locomotive, and foraminous cylinders loosely mounted in the first cylinder and contacting therewith.

4. The combination with a locomotive comprising a boiler having a smoke box and a stack, of partitions in the smoke box spaced to define an opening leading to the stack, a removable plate for the boiler, a plurality of foraminous cylinders disposed one within the other arranged in the opening and means for rotating the outer cylinder from an operating part of the locomotive, the removable plate forming means for permitting the placing 125

and removing of the cylinders in the smoke box.

5. In a locomotive in combination, a flue sheet, a stack and a smoke box located forwardly of the flue sheet, a spark arrester comprising a plate extending downwardly from the top, partially across the smoke box, and having an extension from the lower edge projecting horizontally forward longitudinally of the smoke box and beyond the stack and provided with a downwardly extending portion, a second plate in advance of said first-mentioned plate extending downwardly and rearwardly from the top of the smoke box and toward the said downwardly extending portion of the first mentioned plate, leaving a spaced opening between the forward plate and the plate first-mentioned, a perforated cylinder extending horizontally and transversely of the smoke box and located between the adjacent ends of the above-mentioned plates, and means for rotating said cylinder on its horizontal axis.

6. In a locomotive in combination, a flue sheet, a stack and a smoke box located forwardly of the flue sheet, a spark arrester comprising a plate extending downwardly from the top, partially across the smoke box, and having an extension from the lower edge projecting horizontally forward longitudinally of the smoke box and beyond the stack and provided with a downwardly extending portion of said first mentioned plate, a second plate in advance of said first-mentioned plate extending downwardly and rearwardly from the top of the smoke box and toward the said downwardly extending portion of the first mentioned plate, leaving a spaced opening between the forward plate and the plate first-mentioned, a plurality of perforated and nested cylinders with axes eccentric with respect to each other, said cylinders extending horizontally and transversely of the smoke box and located between the adjacent ends of the above-mentioned plates, and means for rotating said cylinders on their horizontal axes.

7. In a locomotive in combination, a flue sheet, a stack and a smoke box located forwardly of the flue sheet, a spark arrester comprising a plate extending downwardly from the top, partially across the smoke box, and having an extension from the lower edge projecting horizontally forward longitudinally of the smoke box and beyond the stack and provided with a downwardly extending portion, a second plate in advance of said first-mentioned plate extending downwardly and rearwardly from the top of the smoke box and toward the said downwardly extending portion of the first mentioned plate, leaving a spaced opening between the forward plate and the plate first-mentioned, a plurality of perforated and nested cylinders with axes eccentric with respect to each other, said cyl-

inders extending horizontally and transversely of the smoke box and located between the adjacent ends of the above-mentioned plates, means for rotating the outer cylinder on its horizontal axis, and an exhaust pipe extending upwardly through the lower wall of the smoke box through said horizontally-extending portion of said first-named plate, and in line with the stack and back of the perforated cylinders, whereby the exhaust from the exhaust pipe tends to draw the products of combustion through the cylinders and assist the forced draft through said cylinders and to the stack.

In testimony whereof I affix my signature.

AUGUST H. WILMS.
